United States Patent Office

Des. 188,042

Patented May 31, 1960

188,042

COMBINED HANDLE AND LATCH ACTUATING UNIT

Burnie M. Craig, Pasadena, Norman E. Roe, Sierra Madre, and Arthur Brandes, Monrovia, Calif., assignors to Ekco Products Company, Chicago, Ill., a corporation of Illinois

Filed Jan. 11, 1960, Ser. No. 58,996

Term of patent 14 years

(Cl. D10—8)

Fig. 1 is a front view of a combined handle and latch actuating unit embodying our new design.

Fig. 2 is a side view thereof.

Fig. 3 is a top view thereof.

Fig. 4 is an enlarged section taken along line 4—4 of Fig. 1.

We claim:

The ornamental design for a combined handle and latch actuating unit, as shown.
